Primary Examiner—Philip S. Hyder(74) *Attorney, Agent, or Firm*—Coghran Freund & Young LLC; William W. Cochran(57) **CLAIM**

The ornamental design for a box, as shown and described.

DESCRIPTION

FIG. 1 is an isometric view of a box showing my new design.

FIG. 2 is a front view thereof.

FIG. 3 is a top view thereof.

FIG. 4 is a right side view thereof.

FIG. 5 is a left side view thereof.

FIG. 6 is a rear view thereof; and,

FIG. 7 is a bottom view thereof.

The broken line portions of the disclosure are for illustrative purposes only and form no part of the claimed design.
